UNITED STATES PATENT OFFICE.

CHARLES S. JOHNSON, OF BROWNVILLE, MAINE.

DOUBLE-CYLINDER ENGINE.

SPECIFICATION forming part of Letters Patent No. 680,382, dated August 13, 1901.

Application filed January 26, 1901. Serial No. 44,902. (No model.)

To all whom it may concern:

Be it known that I, CHARLES S. JOHNSON, a citizen of the United States, residing at Brownville, in the county of Piscataquis and State of Maine, have invented new and useful Improvements in Double-Cylinder Engines, of which the following is a specification. This invention relates to double-cylinder engines; and the primary object of the invention is to interpose a novel form of gearing between the pistons and the main driving-shaft of the engine, whereby the ordinary fly-wheel may be dispensed with and continuous power imparted to the driving-shaft. By dispensing with the fly-wheel the engine is rendered considerably more compact, requiring less room, and by means of the mechanism hereinafter described continuous motion is imparted to the driving-shaft, and the dead-centers incident to the use of operating-cranks are dispensed with. The mechanism by means of which the reciprocatory movement of the piston-rods is converted into rotary motion comprises a pair of screw-shafts which are mounted for rotary movement in a suitable frame and which are both geared to a common driving or driven shaft. The piston-rods are connected to sleeves which surround the screw-shafts, and said sleeves carry operating devices which engage with the screw-shafts. The pistons are valved so as to reciprocate alternately, and the operating devices for the screw-shafts are so arranged that the respective screw-shafts will be operated in corresponding strokes of the pistons, so that when one operating device is performing its work the other operating device is being retracted, and in this way one or the other of the operating devices is always in action, thereby imparting continuous motion to the driving-shaft of the engine.

The detailed object and advantages of the invention will appear more fully in the course of the ensuing description.

The invention consists in a double-cylinder engine embodying certain novel features and details of construction and arrangement of parts, as hereinafter fully described, illustrated in the drawings, and distinctly pointed out in the claims hereto appended.

In the accompanying drawings, Figure 1 is a plan view of a double-cylinder engine,

showing the improved mechanism for transmitting motion to the driving-shaft. Fig. 2 is a side elevation of the same. Fig. 3 is a vertical cross-section taken on the line 3 3 of Fig. 1. Fig. 4 is also a cross-section through the screw-shafts, guiding-yokes, &c., taken on the line 4 4 of Fig. 1. Fig. 5 is an enlarged vertical longitudinal section through one of the sleeves and the casing carried thereby, showing the relation thereto of one of the screw-shafts and the nut-segments which coöperate therewith. Fig. 6 is a detail longitudinal section through one of the screw-shafts and the nut-segments coöperating therewith. Fig. 7 is a detail elevation of one of the nut-segments.

Similar numerals of reference designate corresponding parts in all the figures of the drawings.

Referring to the drawings, 1 designates the bed-plate of the double-cylinder engine, upon which are mounted the twin cylinders 2, surrounded by steam-chests 3, having in communication therewith the steam-supply pipes 4. The pistons contained within the cylinders are connected with parallel piston-rods 5, which are arranged in the same horizontal plane and which reciprocate through a piston-rod guide 6, arranged at a suitable distance from the cylinders. Each of the piston-rods carries a fixed collar 7, having a laterally-projecting wrist-pin 8, to which is pivotally connected one end of a link 9, the other end 85 of which is journaled on a wrist-pin 10 of a crank-arm 11, fast on one end of a rock-shaft 12, mounted in a sleeve-bearing 13, supported by and preferably formed integral with a pedestal 14, interposed between the cylinders 90 and the piston-rod guide 6. The rock-shaft 12 is also provided at its opposite end with a lug 15, to which is pivotally connected one end of a link 16, the other end of which is pivotally attached to a wrist-pin 17, projecting laterally from a collar 18, fast on the stem 19 of one of the valves operating within one of the steam-chests for controlling the supply of steam to the cylinder for operating the piston mounted therein. The connections 100 above described and arranged between the piston-rods and the valve-stems are so constructed and disposed that the valve-stems are reciprocated alternately in opposite di-

rections and the piston-rods are correspondingly reciprocated alternately in opposite directions.

Each of the piston-rods is provided at its outer end with a terminal fixed collar or annular flange 20, which is received in a circular recess 21 in one end of a sleeve 22. The collar 20 is held in place by means of a keeper-plate 23, which is secured in any convenient manner to the end of the sleeve 22, and in this way a swiveled joint is provided between each piston-rod and its sleeve 22, it being understood that a separate sleeve 22 is employed for each piston-rod.

15 24 designates an oil-hole for supplying lubricating material to the terminal collar 20.

Each of the sleeves 22 is preferably square in cross-section externally and is mounted to slide through a sleeved guide 25, formed in a bearing-standard 26, extending upward from a suitable support or bed-plate 27. The sleeve 22 is provided with a longitudinal bore 28, in which is received a power-converting screw-shaft 29, as clearly illustrated in Fig. 5. The

25 threads of the screw-shaft 29 are so formed as to comprise an abrupt shoulder or face 30, which is substantially at right angles to the axis of the shaft, and an inclined and somewhat rounded tapering surface 31. The 30 threads formed in the manner above stated are designed to be engaged by a pair of oppositely-arranged nut-segments 32, each of which has its inner surface or that surface which bears against the screw-shaft hollowed

35 out or concaved, as shown at 33, and provided with ribs 34, which in effect form segments of threads corresponding in shape to and adapted to engage with the threads of the screw-shaft 29. The heel end of each of

40 the nut-segments 32 is extended laterally and provided with an opening to receive a pivot 35, which may be in the form of a pin or bolt inserted through the sleeve or casing.

One end of the sleeve 22 is enlarged to form 45 a casing 36, which is hollowed out to form a chamber, in which the nut-segments 32 are mounted and adapted to be moved into and out of engagement with the screw-shaft. Each of the nut-segments 32 is backed by an expansive spring 37, one end of which is received in a socket or seat 38 in the casing 36, and the opposite end of which bears against its respective nut-segment for yieldingly urging said segment in the direction of the screw-shaft. It will now be seen that as the sleeve 55 22 is moved longitudinally in one direction the nut-segments will engage positively with the screw-shafts and serve to revolve the latter. When the sleeve is retracted or moved

60 in the opposite direction, the nut-segments ride over the screw-shaft until the limit of the backward stroke of the sleeve is reached, at which point the nut segments or grippers are forced into engagement with the thread 65 of the shaft, so that when the sleeve again resumes its outward movement the nut-segments engage the walls of the thread and im-

part power and rotation to the screw, while the nut-segments of the other screw are being drawn back to their initial starting-point. 70

The casing which forms a part of the sleeve 22 is provided with upwardly and downwardly extending arms 39, which travel in slots or guideways 40 in a pair of guiding-yokes 41 and 42, 41 designating the upper guide-yoke 75 and 42 the lower guide-yoke, said yokes being placed, respectively, above and below the horizontal plane of the screw-shafts and rigidly connected with a central supporting-standard 43, connected at one end to the sleeve-guide 26 and at the opposite end to a bearing-standard 44, in which the screw-shafts are journaled. Each of the arms 39 is provided with an aperture 45, having suitable bearings in its upper and lower walls, in 85 which is disposed a vertical journal or spindle 46, upon which is mounted an antifriction guide-roller 47. These guide-rollers 47 operate longitudinally within the slots 40 of the guiding-yokes and reduce the friction to a 90 minimum.

The screws are provided with integral shaft extensions at their outer ends, which are journaled in standards 44 and 48, and between the standards 44 and 48, said shafts are 95 provided with driving-pinions 49, which mesh with an interposed pinion 50, fast on the main driving or driven shaft 51 of the machine, said shaft 51 being mounted in bearings in the standard 48 and in a terminal bearing-standard 52.

53 designates a power-transmitting or band wheel fast on the shaft 51 and from which the power derived from the engine may be transmitted by suitable belting or gearing to 105 the desired point.

From the foregoing description it will be understood that the piston-rods of the engine are arranged parallel to each other and have an alternating reciprocatory movement and 110 that the operating devices carried thereby cooperate with their respective screw-shafts, so as to drive the same in corresponding throws of the piston-rods. In this way one or the other of the operating devices is always in 115 action and continuous power and rotation are transmitted to the driving-shaft, thus overcoming the dead-centers due to the employment of a crank-axle and pitmen, &c.

I do not desire to be limited to the specific 120 construction and arrangement hereinabove set forth, but reserve the right to change, modify, or vary the construction within the scope of this invention.

Having thus described the invention, what 125 is claimed, and desired to be secured by Letters Patent, is—

1. The combination with a double-cylinder engine and the parallel alternating reciprocating piston-rods thereof; of parallel screws, pinions on the outer ends of the screws, sleeves 130 slidably mounted on the screws and connected to the piston-rods and formed with interior chambers, pivotally-supported nut-seg-

ments in the said chambers and adapted to engage the screws in the outward movement of the sleeves, a driving-shaft and a pinion on the driving-shaft in mesh with the pinions on the screws.

2. The combination with a double-cylinder engine and the parallel alternating reciprocating piston-rods thereof of a mechanism for connecting the reciprocatory motion of the piston-rods into continuous rotary motion, comprising suitably-journalled parallel screws, pinions mounted on the shafts of the screws, a driving-shaft, a pinion mounted thereon in mesh with the pinions of the screws, sleeves connected to the piston-rods and slidably mounted over the screws, and formed with an enlargement having upper and lower arms and an interior chamber, guides in which the arms of the sleeves engage, nut-segments pivotally supported in the chambers of the sleeves and adapted to engage the screws, and springs in the chambers bearing on the nut-segments.

3. The combination with a double-cylinder engine and parallel alternating reciprocatory piston-rods; of parallel screw-shafts geared to the driving-shaft, sleeves connected to the

piston-rods and carrying operating devices for the screw-shafts, the operating devices being arranged so as to drive their respective screw-shafts in corresponding throws of the piston-rods, upper and lower arms connected to the sleeves, and upper and lower guiding-yokes which are slotted to receive said arms.

4. The combination with a double-cylinder engine and parallel alternating reciprocatory piston-rods; of parallel screw-shafts geared to the driving-shaft, sleeves connected to the piston-rods, operating devices carried by said sleeves and co-operating with the screw-shafts, the operating devices being arranged so as to drive their respective screw-shafts in corresponding throws of the piston-rods, vertically-disposed arms projecting in opposite directions from the sleeves, antifriction-rollers carried by said arms, and guiding-yokes having guideways in which the rollers move.

In testimony whereof I affix my signature in presence of two witnesses.

CHARLES S. JOHNSON.
